UNITED STATES PATENT OFFICE.

**SAMUEL S. WALDMAN, OF NEW YORK, N. Y., ASSIGNOR TO EMIL GROSSMAN COMPANY,
OF NEW YORK, N. Y., A CORPORATION OF NEW YORK.**

DESIGN FOR A FOOT-PEDAL.

43,657.

Specification for Design.

Patented Feb. 25, 1913.

Application filed December 7, 1912. Serial No. 735,531. Term of patent 7 years.

To all whom it may concern:

Be it known that I, SAMUEL S. WALDMAN, a citizen of the United States, residing at New York city, in the county and State of New York, have invented a new, original, and ornamental Design for a Foot-Pedal, of which the following is a specification, reference being had to the accompanying drawing, forming a part thereof and

presenting a perspective view of a foot-pedal embodying my design.

I claim:

The ornamental design for a foot pedal, as shown.

SAMUEL S. WALDMAN.

Witnesses:

ALEX. FORSTEIN,
ARTHUR MARION.
